UNITED STATES PATENT OFFICE.

THERESA M. LORENZO, OF BRIDGEPORT, CONNECTICUT.

DESIGN FOR A KNITTED FABRIC.

60,868.

Specification for Design. Patented Apr. 18, 1922.

Application filed October 15, 1921. Serial No. 508,026. Term of patent 7 years.

To all whom it may concern:

Be it known that I, THERESA M. LORENZO, a citizen of the United States, residing at the city of Bridgeport, in the county of Fairfield and State of Connecticut, have invented a new, original, and ornamental Design for a Knitted Fabric, of which the following is a specification, reference being had to the accompanying drawing, forming part thereof.

The figure is an elevation showing my new design as applied to an article of manufacture, in the present instance, a sock.

I claim:—

The ornamental design for a knitted fabric, as shown.

THERESA M. LORENZO.
